UNITED STATES PATENT OFFICE.

DANIEL KOPS, OF NEW YORK, N. Y.

APPAREL-CORSET.

1,105,330.

Specification of Letters Patent. Patented July 28, 1914.

Application filed December 30, 1913. Serial No. 809,447.

To all whom it may concern:

Be it known that I, DANIEL KOPS, a citizen of the United States, residing in the borough of Manhattan, city, county, and 5 State of New York, have invented an Improvement in Apparel-Corsets, of which the following is a specification.

In Letters Patent, No. 1,082,273, granted to me December 23, 1913, there is shown 10 and described an apparel corset, in which the lower front body portion is constructed to closely fit and properly support the abdomen, and which corset is also provided with skirt members independent of the lower 15 front portions of the corset body, in order to provide a garment which will at the same time properly support the abdomen and also produce the prevailing straight front effect, the parts of this corset being so arranged 20 that these functions are performed independently, one of the other. In such a corset, there is employed a front skirt member secured along an upper edge to the corset body a substantial distance from the 25 lower edge of the corset, this member being also secured to the corset body along one side edge, forming a continuation of the skirt and also overlying the part on the lower front portion of the corset body. In 30 the use, however, of a corset so constructed, the skirt portions thereof assume a regular continuity, extending around the body of the wearer, and the front skirt sections are not adjustable to position relatively to the 35 lower front body portion of the corset, due to the fact that at their upper edges they are permanently secured to the corset body. Because of this, these front skirt sections are 40 not adapted to closely fit the groin sections of the body.

Now, the object of my present invention is the provision of a corset so constructed that it properly fits and supports the abdomen, provides for the straight front effect, and 45 suitably confines and shapes the upper fleshy portions of the limbs in substantially the same manner as the corset shown and described in my aforesaid application, but in which the upper portions of the front 50 skirt sections are adjustably secured in position relatively to the lower front portions of the corset body, depending upon the pressure the lower front portions of the corset body are to exert against the body.

55 In my present invention, the front skirt sections complete the continuity of the skirt

members from the rear to the front medial lines thereof, and each front skirt section, at its upper portion, overlies the adjacent lower front portion of the corset body, the upper portions of the front skirt sections are 60 adapted to be adjustably secured in position, and the lower portions of the front skirt sections conform to the upper portions 65 of the limbs of the wearer. Hose supporters or other tension devices are secured to the lower adjacent edges of the front skirt sections and incidentally the tension exerted thereby causes the upper portion of each front skirt section to conform to and closely 70 fit the lower front portion of the corresponding corset body half, and the lower portion of each front skirt section to conform to and closely fit the upper portion of the corresponding limb of the wearer so as 75 to produce a distinct line of demarcation between the abdomen and the limbs of the 80 wearer.

In the drawing, Figure 1 is a front elevation of an apparel corset embodying the 80 features of my present invention. Fig. 2 is an elevation of the lower front portions of the corset illustrated in Fig. 1. Fig. 3 is a view similar to Fig. 2, showing a modified form of the invention, and Fig. 4 is a front 85 edge view of the corset shown in Fig. 3.

Referring to the drawing, and particularly to Figs. 1 and 2, the corset made in accordance with my present invention comprises the corset body halves, indicated re- 90 spectively at 10 and 11, which, as usual, are provided at the front meeting edges with steels 12, suitable fastening devices 13, and also, in suitable positions, with boning or stiffening devices, indicated at 14. 95

The corset body half 10 is provided with a depending skirt 15, and the corset body half 11 with a depending skirt 16. In the form of the invention shown in Figs. 1 and 2, as well as in the other forms, these depending skirts extend from the rear medial lines of the corset body halves, forwardly thereof, to predetermined positions. 100

At the front of the corset, the skirt 15 is provided with a skirt extension or section 17, 105 and similarly the skirt 16 is provided with a skirt extension or section 18. The skirt section 17 is connected at one edge to the front edge of the skirt 18 along a line of sewing 19 which extends upwardly from the bottom edge of the skirt to the lower edge 110 of the corset, as indicated at 20, and also con-

tinues upwardly to the upper corner of the skirt extension, as indicated at 21. Similarly the skirt extension 18 is connected along one edge of the front or forward edge 5 of the skirt 16 along a line of sewing indicated at 22. Extending from the lower edge of the skirt upwardly, the lower edge of the corset is indicated at 23, and the line of sewing 22 is also continued upwardly to the 10 upper corner of the skirt extension, as is indicated at 24, that portion of the skirt extension above the lower edge of the corset, it will be understood, being connected to the body half. These skirt extensions complete 15 the continuity of the skirts from the rear to the front medial lines thereof, and, as is plainly indicated in Fig. 2, the upper portion of each skirt extension overlies the adjacent lower front portion of the corset body 20 halves.

Adjacent the lower ends, the corset steels are provided with hooks 26, adapted to receive the eyelets 25 provided in the upper free or forward corners of the skirt extensions, in order to adjustably attach these 25 parts to the corset body. It will be understood, however, that any suitable means may be employed for attaching the upper adjacent portions of the skirt extensions together 30 or to the corset body, in order to properly secure these parts in position.

Attached to the lower edge of the skirt extension 17 is a hose supporter or tension device 27, and similarly attached to the 35 skirt extension 18 is a hose supporter or tension device 28. In the use of the hereinbefore described garment, the tension applied to the skirt sections by means of the hose supporters is such as to exert both a downward and a lateral hold thereon, so that 40 the upper portions of the skirt sections or extensions lie closely against the adjacent underlying lower front parts of the corset body, and the lower portions of the skirt 45 sections or extensions closely fit the limbs of the wearer, producing a distinct line of demarcation between the abdomen and the limbs, as is indicated in Fig. 1.

Referring to Fig. 3, it will be seen that 50 instead of terminating the front of the corset skirts in a free line, running approximately parallel with the front steels, the front of the skirts may be terminated in a curved line, as indicated at 30, the front 55 portion of the skirt extension being indi-

cated at 29. In this construction, I employ a flap member, indicated at 31, associated with each corset body half. Each of these flap members is secured to the skirt extension, the skirt proper and a portion of the 60 corset body half along the lines of sewing indicated at 32 and 33, the former showing a connection between the flap and the skirt extension, and the latter between the skirt proper and the corset body half, so that the 65 entire distant edge of each flap 31 is secured in position from its lower inner corner, indicated at 34, to its upper inner corner, indicated at 34'. These flap members 31 are provided with eyelets 35, and the corset 70 steels, adjacent the lower ends, with hooks 36, adapted to receive and engage with one of the eyelets 35 to secure the upper portions of the flaps in the desired positions. The flap members 31 are provided with hose supporters or tension devices secured to the lower edges thereof and indicated at 37, and also, as is shown in this figure, additional hose supporters may be provided at the lower edges of the skirts at the sides of the 80 corset. One of these hose supporters is indicated at 38.

Referring to Fig. 4, it will be seen that the lower front portions of the steels are preferably curved inwardly, as is indicated 85 at 39, in order to provide a suitable support for the abdomen.

I claim as my invention:

An apparel corset comprising corset body halves, each having a depending skirt extending from the rear medial line thereof forwardly, skirt sections completing the continuity of the said skirts to substantially the front medial line of the corset and extending an appreciable distance below the 95 front meeting edges thereof, each skirt section being connected along one side edge to its skirt and also to a portion of the corresponding corset body half, means for adjustably securing the adjacent front edges 100 of the said skirt sections in position, and tension devices attached to and extending below the lower front edges of the said skirt sections.

Signed by me this 24th day of December 105
1913.

DANIEL KOPS.
